UNITED STATES PATENT OFFICE.

MYRON E. SPRAGUE, OF PLYMOUTH UNION, VERMONT,

ACETYLENE-GAS GENERATOR.

SPECIFICATION forming part of Letters Patent No. 618,299, dated January 24, 1899.

Application filed November 11, 1897. Serial No. 658,174. (No model.)

To all whom it may concern:

Be it known that I, MYRON E. SPRAGUE, of 5
Plymouth Union, in the county of Windsor
and State of Vermont, have invented a new
and Improved Acetylene-Gas Generator, of
which the following is a full, clear, and exact
description.

My invention relates to an improvement in
acetylene-gas generators, and has for its ob- 10
ject to simplify their construction, to render
their action automatic, so that the supply of
gas is regulated by the amount consumed, and
to increase their safety.

The invention consists in certain improved
constructions, which will be hereinafter de- 15
scribed, and particularly pointed out in the
claims.

Reference is to be had to the accompanying
drawing, forming a part of this specification,
20 in which the figure represents a sectional ele-
vation of the device.

The gas-generator proper, or the chamber
which contains the calcium carbid and within
which the gas is formed, is placed at the
25 bottom of the device. This chamber A may
be made in any suitable shape and is pro-
vided at the top with a filling-opening through
which the carbid may be introduced, said
opening having a removable cover a. A sec- 30
ond opening, having a removable cover a', is
located at the bottom of the chamber A,
through which opening the lime resulting
from the decomposition of the carbid may
be removed. The generator has a number of 35
pipes entering the top thereof and serving to
introduce the water necessary for the pro-
duction of the gas and for carrying away the
gas after being produced. These pipes are
preferably introduced through a removable 40
cover A'.

The pipe E is provided upon the end within
the generator with a sprinkler-head L and
is the pipe through which water is introduced
upon the carbid. This pipe E is connected
45 to the lower part of an intervening chamber
C, which is the diaphragm or valve chamber.
The chamber C has a small chamber e upon
one side thereof and projecting horizontally.
The side C' of the chamber C opposite to the 50
small chamber e is a flexible diaphragm, the
gas and spring pressures on the diaphragm
controlling the admission of water into the

carbid-chamber A. Within said chamber
e is located a valve e', which is connected to
a stem e², passing through and fastened 55
tightly to the flexible diaphragm C' upon the
side of the chamber C opposite the chamber e.

Outside the chamber C is a spring G, coiled
on the outside end of the stem e² and bear- 60
ing against the diaphragm C' on the chamber
C and against a screw G' in an arm G², attached
to the chamber C. The spring G acts upon
the diaphragm C', and thus upon the stem
e², in such a manner as to open the valve e' 65
when there is no pressure of gas on the
diaphragm. The pressure of the spring G
may be regulated by means of the screw G',
which receives the pressure of the outer end
of the spring. The spring G may be set at 70
any tension that the required pressure of gas
calls for. A pipe H connects the chamber
C with the chamber A for the purpose here-
inafter explained.

To the outer end of the chamber e is at-
tached a pipe E', which communicates with 75
the lower part of a water-tank or gasometer
B. This pipe E' is preferably provided with
a valve E², by which the flow of water through
the chamber e and valve e' may be prevented
when desired. It will be seen that when the 80
valve E² is opened the water from the tank B
will flow through the open valve e' into the
chamber C and pass thence through the pipe
E to the generator until enough gas has been
formed to press the diaphragm outward 85
against the pressure-spring G, the diaphragm
pulling the attached valve-stem e² with it and
closing the valve and stopping the flow of
water until the pressure of gas decreases,
when the spring presses the diaphragm in- 90
ward, opening the valve and letting in more
water. The pipe D, which enters the upper
portion of the generator, is carried entirely
about the tank B, passing over the top of the
same and beneath its bottom, and then en- 95
ters the tank at the top and is provided with
a downwardly-extending leg D². As shown
in the drawing, the tank B is provided with
a well B', which is of greater depth than the
body of the tank. The pipe D extends into 100
said well and terminates at the end of the
leg D², at or near the bottom of said well, in
a perforated nozzle d', through which the gas
from the generator passes into the water con-

tained in the tank. The gas then passes up through the water in the tank in a series of small bubbles and is by this action cooled and purified.

5 The object in carrying the pipe D entirely around the tank is to prevent the possibility of water flowing through said pipe from the tank if the apparatus should be upset. Without some safeguard of this sort, if the apparatus be upset there is a possibility of the water flowing into the generator in such large quantities as to cause a rapid generation of gas, which would burst the generator and cause an explosion.

15 The object of the downwardly-extending leg D² is twofold: first, to cool and purify the gas by passing it through the water in the tank, and, second, to prevent fire following an explosive mixture of gas and air back to 20 the generating-tank A. As the gas is drawn off from the tank B the pressure is reduced in the generator, and consequently the pressure in the diaphragm-chamber C and pipe D and pipe H will fall. As the pressure is relieved from the tank B the pressure acting 25 on the flexible diaphragm C' on the chamber C to close the valve e' is reduced until finally the spring G is able to overcome this pressure on the diaphragm, which moving inward 30 opens the valve and admits water into the chamber C. As soon as admitted into the chamber C the water will enter the generator through the pipe E and the generation of gas will commence again. This action will 35 continue until a sufficient amount of gas has been introduced to the chamber C to increase the pressure a sufficient amount on the diaphragm to close the valve e'. As soon as the water thus introduced has been entirely 40 consumed in the manufacture of gas the action will stop, and no more gas will be produced until the pressure within the tank has dropped to such a point as to open the valve e'. It will thus be seen that the action of the device is entirely automatic, the generation of 45 gas depending entirely upon the consumption thereof and being fast or slow according as the gas is used rapidly or slowly.

To more fully guard against a variation in 50 pressure between the chamber C and the generator A and also to prevent interference with the flow of water through the pipe E by the flow of gas therethrough, the additional pipe H is provided, connecting the 55 generator with the chamber C.

A funnel I is mounted upon the upper side 60 of the tank B and is provided with a valve I', by means of which water may be introduced to the tank as desired. This tank serves a double purpose, acting as a reservoir 65 for storing water and as a gasometer or holder for the gas. It also incidentally serves still another purpose, as a purifying-chamber for the gas. A cock for an air-vent to open when filling with water is placed near the top of the tank B.

A pipe J is attached to the tank B for con-

ducting the gas to any point where its use is desired. To prevent the possibility of explosion due to mixture of air with the gas at 70 the time the apparatus is first set in use, I provide the pipe J, at some point between the tank and the burner, with a chamber containing a piece of fine wire-gauze J', which extends entirely across the chamber and will 75 prevent flame from passing from one side to the other. The pipe J is also provided with a suitable valve J², located at any convenient point, and by means of which the pipe may be closed. The pipe D is also provided with 80 a valve d, similar to the valve J².

It will be seen that by the adjustment of the spring G the action of the apparatus may be readily controlled. By reducing the pressure of the spring the pressure in the 85 diaphragm-chamber C must drop lower before the valve e' will open. The gas is thus used at a small pressure. It is thus possible by this simple device to thoroughly control the operation of the device and maintain any 90 desired pressure in the pipes.

Having thus described my invention, I claim as new and desire to secure by Letters Patent—

1. A gas apparatus, comprising a generator, 95 a tank located above the generator for containing water, a gas-discharge pipe leading from the generator to said tank and discharging into the lower portion of said tank, a valve-chamber, the side of which chamber opposite the valve is a flexible diaphragm, between the generator and tank, a pipe connecting the valve or diaphragm chamber with the tank, a valve controlling the entrance of water from the tank and opening against the pressure of water, a stem upon said valve extending to the flexible diaphragm on the side of the valve-chamber opposite the valve and firmly fixed to the flexible diaphragm, a spring pressing on said diaphragm and acting to open the valve 100 when there is no pressure in the generator, means for adjusting the tension of the spring, and a pipe connecting the lower part of the chamber with the generator, whereby water admitted to the chamber will be discharged 105 upon the carbid in the generator, substantially as described.

2. A gas apparatus, comprising a generator, a water-reservoir located above the generator, a gas-discharge pipe leading from the 110 generator to said tank and discharging into the lower portion of said reservoir, a valve or diaphragm chamber between the generator and tank, a pipe connecting the valve-chamber with the tank, a valve, operated by the 115 movements of the flexible diaphragm, the movements being made by the increase or decrease of the pressure of gas in the generator and by the pressure of the spring on the diaphragm, said valve controlling the entrance 120 of water from said tank and opening against the pressure of water, a stem upon said valve extending through the diaphragm outside the chamber, a spring pressing on the diaphragm 125

where the valve-stem is fastened to the dia-
phragm and serving to open the valve, means
for adjusting the tension of the spring, a pres-
sure-equalizing pipe connecting said cham-
ber and the generator, and a water-convey-
ing pipe connecting the lower part of the
chamber with the generator, whereby water
admitted to the chamber will be discharged
upon the carbid in the generator, substan-
tially as described.

3. In a gas apparatus, the combination with
a generator, a tank above the generator, and
a pipe leading from the generator to the tank,
of a chamber intermediate of the generator
and tank and communicating with the genera-
tor, the said chamber having one side in
the form of a diaphragm and provided at the
side opposite the diaphragm with a valve-
chamber, a pipe leading from the tank to the
valve-chamber, a valve in said chamber and
having its stem secured to and passing through
the diaphragm, an arm, a screw in the arm
and a spring surrounding the valve-stem be-
tween the screw and diaphragm, substantially
as described.

4. In a gas apparatus, the combination with
a generator, and tank above the generator
and connected therewith by a pipe, of a cham-
ber between the tank and generator and hav-
ing one side in the form of a diaphragm, the
bottom of the said chamber being connected

with the generator by a pipe, a valve-cham-
ber at one side of the said chamber and con-
nected with the bottom of the tank by a pipe,
a valve in the valve-chamber and having its 35
stem secured to the diaphragm of the said
chamber, and a spring bearing upon the said
diaphragm, substantially as described.

5. A gas apparatus, consisting of a genera-
tor, a tank above the generator and provided 40
with a well, a pipe leading from the genera-
tor into the tank, the said pipe being provided
with a leg extending down into the well of
the tank, a chamber between the tank and
generator and having one side in the form of 45
a diaphragm, a pipe connecting the bottom
of the chamber with the generator, a valve-
chamber on the side of the chamber opposite
the diaphragm, a pipe connecting the valve-
chamber with the bottom of the tank, a valve 50
in the valve-chamber and having its stem se-
cured to and passing through the diaphragm,
an arm, a screw in the arm, a spring on the
projecting end of the valve-stem between the
screw and diaphragm, and a pipe leading 55
from the upper part of the diaphragm-cham-
ber to the generator, substantially as herein
shown and described.
